US00D680223S

(12) **United States Design Patent**
Jamison et al.

(10) **Patent No.:** **US D680,223 S**
(45) **Date of Patent:** **** Apr. 16, 2013**

(54) **EXAMINATION CHAIR**

(75) Inventors: **Chris M. Jamison**, West Chester, OH (US); **H. Ray Wright**, Loudon, TN (US); **Antonio Belton**, Richton Park, IL (US); **Dominik J. Beck**, Menlo Park, CA (US)

(73) Assignee: **Reliance Medical Products, Inc.**, Mason, OH (US)

(**) Term: **14 Years**

(21) Appl. No.: **29/404,346**

(22) Filed: **Oct. 19, 2011**

(51) LOC (9) Cl. **24-02**

(52) U.S. Cl.

USPC **D24/178**; D6/336

(58) **Field of Classification Search** D24/172, D24/176-179, 183-185; D6/334, 336, 360-361, D6/501-502, 335, 367, 500; D10/46; 248/127; 297/330, 391, 411.2, 445.1, 447.2, 452.28, 297/452.29; 351/245, 200, 244, 246; 433/33

See application file for complete search history.

(57) **CLAIM**

The ornamental design for an examination chair, as shown and described.

DESCRIPTION

FIG. 1 is a front perspective view of the examination chair according to the invention.

FIG. 2 is a front elevational view thereof.

FIG. 3 is a left side elevational view thereof.

FIG. 4 is a right side elevational view thereof.

FIG. 5 is a rear elevational view thereof.

FIG. 6 is a top view thereof; and,

FIG. 7 is a bottom view thereof.

Any elements shown in broken lines form no part of the claimed invention in this application, and are instead included to show environmental aspects of the claimed invention.

1 Claim, 6 Drawing Sheets
